ELECTRIC HORN

Gustav Zeininger, Oberesslingen, Germany, assignor to Robert Bosch Aktiengesellschaft, Stuttgart, Germany

Application October 24, 1932, Serial No. 639,363
In Germany November 5, 1931

12 Claims. (Cl. 177—7)

The present invention relates to electric horns, particularly for vehicles.

In electromagnetic horns for motor vehicles, the armature is rigidly secured, as a rule, to the diaphragm by a screwed bolt.

The diaphragms are ordinarily of sheet metal and are rigidly clamped at their margins so that there exist always certain tensions or strains in the diaphragm and also in the rigid fastening 10 of the armature which tend to prevent the diaphragm from vibrating exactly axially or in a direction perpendicular to the plane of the diaphragm and the operation of the entire vibrating system is forced or constrained. Such 15 dis- placed and unequal vibration of the diaphragm and armature results in variations in the tone; and differences in the size of the air gap will affect very materially the proper operation of the horn. Furthermore, the purity of the tone is impaired because such improper vibration increases 20 the wear on the interrupter contacts and on the guide for the diaphragm and armature.

The present invention has for its object to remove the drawbacks which result from the usual 25 rigid fastening of the armature to the diaphragm. For this purpose, according to the invention the armature is secured to the diaphragm by a bolt or similar fastening means with the interposition of a resilient member mounted coaxially of said 30 bolt and resilient uniformly to the axis thereof so as to press uniformly on the diaphragm, the said resilient member being tensioned to such an extent that it behaves like a rigid member in holding the armature and diaphragm together but is 35 sufficiently resilient to avoid or compensate for undesirable stresses consequent upon fastening with rigid means.

To employ nuts, together with a slotted washer, for securing the armature is not novel, but these 40 slotted washers are not suitable for the present purpose, because they are not resilient uniformly to the axis of the fastening bolt and consequently only produce a very unilateral stiffening or staying with resultant undesired tensions or strains.

The invention is more particularly described with reference to the accompanying drawing in which three examples of construction of the invention are illustrated and in which:—

Figure 1 is a longitudinal section through one 50 example.

Figure 2 a longitudinal section through the second example; and

Figure 3 a cross-section through a curved 55 springy disc for use in the third example of construction.

In Figure 1, an electromagnet 1 has a plate-shaped armature 2, which is secured by a bolt 3 to the diaphragm 4. A plate-shaped oscillator 5 is connected to the diaphragm 4 by the bolt 3, which has a cylindrical enlarged part, which is located in a longitudinal bore passing through the electromagnet 1, and is held at its end by a guide spring 6.

The armature 2 is fitted between two intermediate pieces 7 and 8, which are seated with some play on the bolt 3, and are ball-shaped on their two end faces which are directed away from each other. These bear respectively against a cone-shaped recess 9 in the bolt 3 and against a ball-shaped recess in a disc 10 which is located 15 at one side of the diaphragm 4. At the other side of the diaphragm 4 is a disc 11 which carries a pin 12 for centering the armature 2. Between the disc 11 and the oscillator 5 a distance disc 13 is arranged, which prevents the diaphragm 4 20 when oscillating from touching the oscillator 5. The free end of the bolt 3 is provided with a thread which carries a nut 14 which bears through a helical spring 15 against the oscillator 5. 25

The ball-joint mode of fastening the armature 2 enables an exact adjustment of the armature 2 in a plane parallel to its attraction face. The air gap between the armature 2 and its attraction face may, if desired, be adjusted by inserting a suitable washer between the armature 2 and the intermediate piece 8. The fastening nut 14 is finally tightened up and then again slackened by about a quarter turn. By this means undesired tensions in the diaphragm and armature fastening are compensated for. Consequently, the note produced is much more uniform than in the rigid screwing up of the oscillating system; also small differences or variations in the exact size of the air gap are compensated for so that such great 40 care in adjusting the air gap as would otherwise be necessary need not be taken. The adjustment of the horn is thereby much less delicate than in the rigid fastening and the oscillating system works without constraint, whereby reliable operation is ensured even after long use. 45

It is not necessary that the springy member should be supported against the fastening nut. On the contrary, the springy member may, for example, be displaced even to the other end of 50 the bolt 3, as shown in Figure 2. The construction therein shown is essentially the same as in the first example, except that the bolt 3 is carried through to a flange 17 and the ball end face of the intermediate piece 7 bears against the cone- 55

shaped recess 9 of an intermediate disc 18. The spiral spring, here marked 19, is compressed between this intermediate disc 18 and the flange 17, and the fastening nut 14 is tightened against 5 the oscillator 5.

As will be seen from Figure 2, the spiral spring lies within the pot-shaped casing 20 closed by the diaphragm 4. This arrangement has the advantage that the bolt 3 need not project considerably beyond the oscillator 5, as may be desirable, for instance, in horns without a projecting trumpet.

The same advantage can however, also be obtained in the arrangement according to Figure 15 1, by using a dished springy disc 21 (Figure 3) instead of the spiral spring 15.

As will be seen from Figures 1 and 2, the air-gap between the armature 2 and its attraction face is not appreciably varied by adjusting the spring 15 or 19 by means of the bolt 3 in the manner described.

There is nothing to prevent the resilient fastening of the armature being also used in horns without an oscillator. In this case, the distance piece 13 and the oscillator 5 are simply omitted. The use of a ball-joint type of armature adjustment is also not necessary, and another mode of supporting the armature may be adopted than by 25 the guide spring 6.

30 I declare, that what I claim is:

1. An electromagnetic horn comprising a casing, an electromagnet mounted in said casing, an armature having an opening therein, an interrupter operated by said armature, a diaphragm 35 secured at its periphery to said casing and having an opening therein, a bolt having an abutment thereon passing through the openings in said armature and said diaphragm, a ball and socket joint between said armature and said bolt, and 40 a member resilient uniformly to the axis of said bolt coacting with the abutment on said bolt to exert a high tension on said diaphragm and said armature to resiliently clamp said armature and diaphragm together and to resiliently mount said 45 armature on said diaphragm.

2. An electromagnetic horn comprising a casing, an electromagnet mounted in said casing, an armature having an opening therein, an interrupter operated by said armature, a diaphragm 50 secured at its periphery to said casing and having an opening therein, a bolt having an abutment thereon passing through the openings in said armature and said diaphragm, and a member resilient uniformly to the axis of said bolt and 55 arranged co-axially on said bolt in the chamber formed by said casing and said diaphragm acting on said diaphragm and said armature and coacting with the abutment on said bolt to resiliently clamp said armature and diaphragm together and to resiliently mount said armature on 60 said diaphragm.

3. In an electromagnetic horn, the combination 65 with a casing, a vibratory diaphragm secured at its periphery to said casing and an electromagnet secured to said casing, of an armature, fastening means carried by said diaphragm for securing said armature thereto, and resilient means mounted coaxially of said fastening means and resilient uniformly to the axis thereof, said 70 resilient means acting on said diaphragm and said armature and coacting with said fastening means to resiliently clamp said armature and diaphragm together and to resiliently mount said armature on said diaphragm, said resilient means being tensioned so highly that said mounting is

comparatively unyielding but is sufficiently resilient to compensate for undesired tensions in the diaphragm and mounting.

4. In an electromagnetic horn, the combination 5 with a casing, a vibratory diaphragm secured at its periphery to said casing and an electromagnet secured to said casing, a fastening member carried by said diaphragm, an armature, ball and socket means for mounting said armature on said fastening member, and means resilient uniformly to the axis of said diaphragm and carried by said fastening member and acting on said armature and diaphragm and coacting with said fastening member to resiliently clamp said armature and diaphragm together and to resiliently 10 mount said armature on said diaphragm.

5. An electromagnetic horn comprising a casing, an electromagnet mounted in said casing, an armature, a diaphragm secured at its periphery to said casing and spaced from said armature, a 20 bolt carrying said armature and passing through said diaphragm to secure said armature thereto, and resilient means carried by said bolt and resilient uniformly to the axis thereof, said resilient means coacting with said bolt to resiliently clamp 25 said diaphragm and armature together and to resiliently mount said armature on said diaphragm, said resilient means being tensioned so highly that said mounting is comparatively unyielding but is sufficiently resilient to compensate 30 for undesired tensions in the diaphragm and mounting.

6. An electromagnetic horn comprising a casing, an electromagnet mounted in said casing, an armature having an opening therein; a dia- 35 phragm secured at its periphery to said casing and having an opening therein, a bolt passing through the openings in said armature and said diaphragm, means spacing said diaphragm from said armature on said bolt, and a resilient mem- 40 ber carried by said bolt and resilient uniformly to the axis thereof acting on said armature and diaphragm to resiliently urge them together against such spacing means and coacting with said bolt to resiliently fasten said armature to 45 said diaphragm.

7. An electromagnetic horn comprising a casing, an electromagnet mounted in said casing, an armature having an opening therein, a dia- 50 phragm secured at its periphery to the casing and having an opening therein, spacing means between said armature and diaphragm, a bolt passing through said openings in said armature and diaphragm and having an adjustable nut co- 55 operating with said bolt to adjustably clamp said armature, spacing means and diaphragm together, and a spring member mounted on said bolt between said nut and the head of the bolt and resilient uniformly to the axis thereof to resiliently urge said armature and diaphragm together, the tension of said spring member being adjustable by said nut without altering the spacing between said armature and diaphragm.

8. An electromagnetic horn as claimed in claim 7 in which the adjustable nut is arranged on the end of the bolt towards the sound opening of the horn and the spring member is arranged between the adjustable nut and the diaphragm.

9. An electromagnetic horn comprising a cas- 70 ing having an open end, a diaphragm, means se- curing the diaphragm to the open end of the cas- ing, an electromagnet secured in the casing, an armature for the electromagnet, ball and socket means between the armature and diaphragm, clamping means for holding the armature, ball 75

and socket means and diaphragm together whereby the armature is secured to said diaphragm, and spring means resilient uniformly to the axis of said diaphragm and mounted between the clamping means and the armature, ball and socket, and diaphragm assembly.

10. An electromagnetic horn comprising a casting having an open end, a diaphragm, means securing the diaphragm to the open end of the casting, an electromagnet secured in the casing, an armature for the electromagnet, a ball and socket joint between the armature and diaphragm, a bolt for clamping the armature and diaphragm together whereby the armature is secured to said diaphragm, a ball and socket joint between said bolt and said armature, and a spring resilient uniformly to the axis of said bolt and mounted on said bolt and urging said armature and diaphragm together.

20 11. An electromagnetic horn as in claim 10, in which one element of each of the ball and socket

joints is loosely mounted on said bolt, said loosely mounted elements mounting said armature on said bolt.

12. An electromagnetic horn comprising a casting having an open end, a diaphragm, means securing the diaphragm to the open end of the casting, an electromagnet secured in the casing, an armature for the electromagnet, clamping means for holding said armature and diaphragm together and for mounting said armature on said diaphragm, and spring means resilient uniformly to the axis of said diaphragm and mounted between the clamping means and the armature and diaphragm assembly, said spring means being tensioned so highly that the mounting of said armature on said diaphragm is comparatively unyielding but is sufficiently resilient to compensate for undesired tensions in said diaphragm and mounting.
